WILLIAM H. STEDMAN, OF HARTFORD, CONNECTICUT, ASSIGNOR TO THE MERROW MACHINE COMPANY, OF HARTFORD, CONNECTICUT, A CORPORATION OF CONNECTICUT.

TRIMMING MECHANISM FOR SEWING-MACHINES.

SPECIFICATION forming part of Letters Patent No. 733,760, dated July 14, 1903.

Application filed August 6, 1902. Serial No. 118,680. (No model.)

To all whom it may concern:

Be it known that I, WILLIAM H. STEDMAN, a citizen of the United States, residing in the city and county of Hartford, State of Connecticut, have invented certain new and useful Improvements in Trimming Mechanism for Sewing-Machines; and I do hereby declare the following to be a full, clear, and exact description of the same, reference being had to the accompanying drawings, forming a part of this specification, and to the figures of reference marked thereon.

This invention relates to that class of trimming mechanism embodying a vibrating and a relatively fixed cutter operating conjointly with a feeding mechanism to effect the trimming of the material as it is fed forward.

The invention embodies certain novel constructions, arrangements, and combinations of various parts and elements, whereby the application of trimming mechanism to a type of machines hereinafter more particularly designated is effected; but the improvements constituting this invention are not all intended to be exclusively so utilized, some of them being applicable to trimming mechanism in general. These improvements are especially designed for use in connection with sewing-machines now in use and commonly known as "overseaming-machines," for a detailed illustration and description of which reference may be had to United States Patents Nos. 414,718 and 591,049.

In the drawings, Figure 1 is a front elevation of a machine, showing the present improvements applied thereto. Fig. 2 is a rear elevation of the end of the machine at which the trimming mechanism is located, the other portion of the machine being broken away and the feed-dog removed. Fig. 3 is an end elevation of the machine as viewed from the left hand of Fig. 1 with overlying portions broken away and removed. Fig. 4 shows the present improvements, partly in elevation and partly in section, on a somewhat enlarged scale, the outline of the machine-frame being indicated in dotted lines. Fig. 5 shows the elements of Fig. 4, partly in front elevation and partly in section. Fig. 6 is a plan view 50 of the needle-plate and adjacent parts relat-

ing to the present invention. Fig. 7 is a front elevation showing the means whereby the stationary cutter is adjustably supported and held. Fig. 8 is a sectional elevation showing the means whereby the vibrating cutter is supported and secured. Fig. 9 is a front elevation of a portion of the carrier for the vibrating cutter and its supports. Fig. 10 is a top view of the carriage to which the vibrating cutter is secured, the bolt which clamps the carriage to the carrier being shown in cross-section. Fig. 11 includes side and edge views of a clamp for the fixed cutter. Fig. 12 embraces end and side elevations and a cross-sectional view of the vibrating cutter.

Like numerals of reference in the several figures indicate the same parts.

The number 10 denotes the main-frame housing or casing of the machine; 11, the head; 12, the main shaft; 13, the driving-pulley, and 14 a second shaft above and parallel with the main shaft. The shafts 13 and 14 bear, respectively, cam-cylinders 12^a 14^a, having intermeshing gears 12^b 14^b for insuring the unitary rotation of the shafts and cam-cylinders. The cam-cylinders serve to actuate certain elements of the stitch-forming mechanism; but as the same form no part of this invention a full illustration and description are not deemed necessary.

The number 10^a denotes a door for closing an opening in the frame 10, through which the interior of the machine may be reached. The second shaft 14 projects through the end wall of the frame 10 and bears an eccentric-pin 15, connected by a link 16 with the needle-carrier 17, the latter being pivotally secured to the end wall of the frame. The needle 18 is mounted in the carrier 17 and through the described train of mechanism is reciprocated in a path concentric with the pivotal support of the needle-carrier.

The machine is provided with a needle-plate 19, supported beneath the head 11, and also preferably with a variety of "four-motion" feed now in common use and including a presser-foot 20. The feed is driven from the main shaft 12, and serrated portions of the feed-dog 21 operate through openings 19^a in the needle-plate 19.

The various elements thus far described are adapted to perform their respective functions in the usual manner and are illustrated and pointed out in order that the relation of 5 the present improvements thereto may be more clearly comprehended from the following description:

As is usual in overseaming-machines, the trimming-cutters are located and adapted to 10 coact in substantially the plane of the top of the needle-plate and somewhat in advance and to the right of the point at which the needle penetrates the material (as the machine is viewed from its front side) in order 15 to that the overseam - stitches may be formed upon the trimmed edge of the material and at a point in proximity to the trimmer. Of the said cutters one is adapted to vibrate and is denoted by the number 22. The companion 20 cutter is preferably fixed relatively to the vibrating cutter when the trimming mechanism is in operation and in said drawings is denoted by the number 23. The vibrating cutter is operated by a lever or carrier 24, extending 25 transversely to the shaft 14 and through intermediate mechanism receives vibratory motion from the said shaft. The rear end of the carrier 24 projects through the wall of the machine-frame 10 and is pivoted 30 in a cap 25 (secured to the back side of the said frame) upon a pin 26, journaled in the cap 25, the axis of the said pin being preferably located in the plane of the top of the needle-plate 19. To support the forward end 35 of the carrier 24 and impart vibratory motion thereto and to the cutter 22, the shaft 14 is provided with an eccentric 27, preferably formed on or attached to the cam-cylinder. The eccentric 27 is adapted to rotate in a 40 block 28, which is slidably mounted in a slot or opening 24^b in the lever 24, the said opening being preferably provided with a removable cap 24^c. At its forward end the lever 24 has a laterally-extending projection 24^d 45 provided with a dovetail groove 24^e, in which a carriage 29 is adjustably secured, the cutter 22 being in turn secured to the carriage in a manner to be presently explained. To insure the retention of the cutter 22 in proper 50 coaction with the cutter 23 after adjustment, the forward end of the lever 24 is preferably an exact working fit between the end of the cam-cylinder 14^a and the adjacent end wall of the machine-frame 10, (see dotted lines in 55 Fig. 6,) thus preventing sidewise spring or play of the lever 24, while permitting of its vertical movement. With this arrangement the lever 24 is located within the machine-frame 10, being thereby protected from dirt 60 and from injury or entanglement with the clippings occasioned by the trimming operation and in a large degree confines the scattering oil to the interior of the machine. Further, the said lever is hidden from view, 65 thereby preserving in a large degree the usual exterior appearance of the machine.

The vibrating cutter 22 is of peculiar and

novel construction. It is preferably made of a bar of steel angular in cross-section, with its cutting end at an acute angle to the longitudinal axis of the bar. Said cutter is therefore arranged in its support in a diagonal position substantially corresponding to the angle of its cutting end. The cutting-angle of the cutter may, however, be square or at an 75 angle of ninety degrees or any suitable acute angle, and it will be obvious that it will be so disposed or mounted in its support that its cutting - face shall be in substantially the same plane as its movements. The fluke or 80 wing 22^a of the cutter-bar is preferably rounded at its edge and acts as a guard or guide, remaining in contact with the adjacent face of its companion cutter 23 at all times, while the cutting edge 22^b acts as a shear against 85 the cutting edge of the said companion cutter. The cutter 22, as shown in the drawings, is made with its wings at an angle of substantially ninety degrees, which has been found preferable for the machine illustrated, 90 but obviously is not essential. It will be observed that this knife can be ground and reground on its angular cutting end as it wears or becomes dull without destroying its form and that of its guard or guide. Cutters provided with guides or guards as heretofore made and used in sewing - machines have been ground or sharpened on the angle away from or not in contact with the face of the companion cutter and have been difficult to 100 grind or sharpen, especially at the point where the guard joins the cutting edge. The wear of the guard has also much injured its usefulness. The cutter, made in angular form and ground or sharpened across or upon the 105 cutting end, including the whole surface of the guard, can be reground or sharpened and entirely restored to its original form and efficiency, and, furthermore, the form of this cutter conduces to its rigidity and durability. 110

Referring now to the manner in which the vibrating cutter 22 is secured to the carriage 29, it will be seen that the said carriage has on its front face a diagonal groove 29^a for the reception of the cutter and also an integral 115 block 29^b.

The number 30 denotes a clamp secured to the block 29^b by a screw 31, and the said clamp has two wings 30^a, adapted, respectively, to engage the carriage 29 and the cutter 22 to clamp the latter in the groove in the carriage. 120

As before stated, the trimming-cutters engage each other in substantially the plane of the upper face of the needle-plate. With the 125 diagonally-supported vibrating cutter 22 it will be apparent that the position of the cutter in the groove determines the elevation of the cutting edge, the sliding of the cutter acting to raise or lower the said edge, and to enable the cutter 22 to be readily positioned the carriage 29 is provided with a projection 29^c, located directly over the cutter and of such length that its end and the cutting end of the 130

cutter register when the latter is in the proper position for operation. The projection 29^e therefore not only forms a gage by means of which the diagonal adjustment of the cutter 23 in the carriage 34 is readily indicated, but also forms a backing to receive the thrust or pressure of the cutter immediately in line with the point at which the cutters operate.

As before mentioned, the carriage 29 is adjustably secured to the projection 24^d of the vibrating carrier or lever 24, the parts being secured by providing a hole 24^f, Fig. 9, through the said projection, such hole forming a channel across the bottom wall of the dovetail way 24^e and the lower portion of the front face of the projection 24^d. The dovetail rib 29^e of the carriage 29 is cut away, as at 29^f, Fig. 10, to permit a bolt 32 to be located in the hole and channel 24^f, the said bolt being provided with a head 32^a, shaped substantially like the lower portion of the projection 24^d, and it is further provided with a nut 32^b. It will be obvious that upon tightening the nut 32^b the bolt-head 32^a will be drawn into engagement with the dovetail rib 29^e of the carriage 29, thus clamping the latter to the projection 24^d of the carrier 24, or upon loosening the nut 32^b the said carriage may be adjusted laterally within the limits of the cut-away portion 29^f of its dovetail rib.

In the machine shown in the drawings the adjustment of the carriage 29 is intended to be made by hand or with the use of any convenient tool; but obviously ordinary mechanical means may be employed when found desirable.

For supporting the cutter 23 a standard 33 is provided, located at the left of the machine-frame 10 as the machine is viewed from its front side. The cutter 23 is secured to a carriage 34, adjustably mounted upon the standard 33, the latter being preferably provided with a dovetail way 33^a, Fig. 7, for the reception of a dovetail rib 34^a on the said carriage. The adjustment of the said carriage is toward and from the machine proper and is effected by a screw 35, mounted in the standard 33 and having a flange 35^a entering a slot in the carriage 34, as best shown in Fig. 5. To retain the carriage 34 in an adjusted position, substantially the same means are employed as are employed in connection with the carriage 29 and already described—viz., the standard 33 is provided with a hole for the reception of a bolt 36, having a head 36^a, suitably shaped to engage and clamp the dovetail rib 34^a of the carriage 34. A covered nut 36^b is seated in the standard 33 and is adapted to be rotated to draw the bolt into itself and the bolt-head 36^a into clamping contact with the dovetail projection 34^a, or the said nut may be rotated to release the bolt-head and projection to permit of adjustment of the carriage 34.

At the end of the carriage 34 on which the cutter 23 is secured the said carriage is

formed with an upwardly-extending portion 34^b to provide a backing and support for the cutter and to prevent deflection thereof, and in the preferred construction the top surface of said upwardly-extending portion is nearly in or slightly above the plane of the upper surface of the needle-plate to permit the presser-foot to clamp the fabric tightly at this point while the cutting is going on. The forward corner 34^d, Fig. 7, of the top of the carriage extension 34^b is rounded to facilitate the passage of the fabric, as is also the corresponding corner of the cutter 23. The cutter 23 is preferably located in a diagonal groove 34^c, formed in the carriage 34 and in its upwardly-extending portion 34^b, the cutter being retained in the said groove by a clamp 37, located in a horizontal groove or recess in the carriage 34, and when in position therein is substantially flush with the face of the said carriage. The clamp 37 at its end adjacent the cutter 23 is adapted to engage the edge of the said cutter and is itself held by a screw 38, Fig. 4, located in the carriage 34, and which when turned inward forces and holds the clamp in contact with the edge of the cutter and clamps the latter against the opposite wall of the diagonal groove 34^c. To enable the clamp-screw 38 to be readily reached and manipulated, an elongated slot 38^a, Fig. 1, is provided in the standard 33. The clamp 37 has at its end adjacent the cutter 23 a groove 37^a to receive the cutter and preferably a shoulder or wing 37^b to engage the face of the cutter, as shown in Fig. 7, to prevent lateral displacement of the said cutter when loosened.

The confronting portions of the machine-frame 10 and the standard 33 are cut away to receive a chute 39, the chute in turn being cut away, as at 39^a, where it would otherwise interfere with the trimming mechanism, said chute being also provided with an inclined wall 39^b, on which the clippings from the cutters fall and travel from the machine.

The standard 33 in addition to supporting the carriage 34 also supports the needle-plate 19, in one of the openings 19^a of which latter the projection 34^b of the carriage and the fixed cutter is located, as best shown in Fig. 6.

When a machine of the type shown and described is fitted up with the improved trimming mechanism, certain arrangements of the threads are desirable to facilitate the threading of the looper or loopers. The thread 40, which is conducted to one of the loopers, is introduced to the interior of the machine through a diagonal tube 41 in a manner similar to that commonly practiced, the said tube being placed low enough to carry the thread 40 beneath the lower end of the chute 39. The looper-thread 42 is carried beneath the lower end of the chute 39 through guide-eyes 43 44 and is then led upward to a block 45, secured to the standard 33 and having a groove 45^a therein, through which the thread renders to the looper 46, reciprocating horizontally beneath the needle-plate

in a path at the rear of the end of the said block 45. The block 45 serves not only to conduct the thread, but also constitutes a means whereby the needle-plate may be readily positioned on the standard 33, the upper edge of the said block extending into a groove in the under side of the needle-plate to locate the same laterally, as shown in Figs. 1, 4, and 5. It also forms a support for the said needle-plate directly under the presser-foot and in proximity to the needle-hole.

The machine shown in the drawings is arranged to trim and finish small tubular fabric, and when thus arranged the described support for the needle-plate is desirable, inasmuch as the principal support for the needle-plate is far forward of the needle-hole to accommodate the adjustable lower cutter, as well as the feed. In order to leave the desired space under the outside edge of the needle-plate for the returning edge of small tubular work, this block 45 is placed as near to the feed and is made as thin as possible.

The lower end of the chute 39 projects beyond the machine-frame 10 to protect the threads 40 and 42, passing beneath the same, and as a further protection for the thread 42 the standard 33 is provided with ribs 33^a, between which the said thread renders in its course from the eye 44 to the block 45. The vertical wall of the chute is also formed to project beyond the face of the door 10^a as a further protection for the threads from contact with the clippings.

Having thus described my invention, what I claim as new, and desire to secure by Letters Patent, is—

1. In a sewing-machine, in combination, a chambered main frame adapted to receive portions of the machine's mechanism, trimming mechanism including a vibrating and a co-operating relatively fixed cutter, a carrier for the vibrating cutter located within the chamber and projected at its pivoted end through an opening in the chamber-wall, a cap within which the said end of the carrier is pivotally supported secured to the chamber-wall to close the opening therethrough for the purpose set forth and substantially as described.

2. In a trimming mechanism for sewing-machines, the combination with a fixed cutter, of a co-operating reciprocating cutter diagonally supported relatively to the plane of the face of its cutting end and diagonally to the plane of the work-support and arranged to reciprocate bodily in a plane parallel with the plane of its cutting end, said reciprocating cutter and its co-operating cutter both being adjustable bodily in a line parallel with the work-support to vary the width of the trimmed edge, and means for actuating the reciprocating cutter, substantially as described.

3. In a trimming mechanism for sewing-machines, the combination with a fixed cutter, of a co-operating reciprocating cutter diagonally supported relatively to the plane of

the face of its cutting end and diagonally to the plane of the work-support and arranged to reciprocate bodily in a plane parallel with the plane of its cutting end, said reciprocating cutter being bodily adjustable by independent means both in a plane at right angles to the plane of the face of its cutting end and in a plane diagonal with respect to the plane of the face of its cutting end and means for actuating the said cutter; substantially as described.

4. In a trimming mechanism for sewing-machines, the combination with a fixed cutter, of a reciprocating-cutter carrier, a carriage laterally adjusted on said carrier, a cutter on the carriage, diagonally supported relatively to the plane of the face of its cutting end and diagonally to the plane of the work-support and arranged to reciprocate bodily in a plane parallel with the plane of its cutting end and means for actuating the carrier; substantially as described.

5. In a trimming mechanism for sewing-machines, the combination with a fixed cutter, of a reciprocating-cutter carrier, a carriage adjustably mounted on said carrier, a cutter on the carriage diagonally supported relatively to the plane of the face of its cutting end and diagonally to the plane of the work-support and arranged to reciprocate bodily in a plane parallel with the plane of its reciprocating cutting end, said cutter being bodily adjustable on the carriage diagonally to the plane of the face of its cutting end and means for actuating the carrier; substantially as described.

6. In a trimming mechanism for sewing-machines, the combination with a fixed cutter, of a reciprocating-cutter carrier, a carriage laterally adjustable on said carrier, a cutter on the carriage diagonally supported relatively to the plane of the face of its cutting end and diagonally to the plane of the work-support and arranged to reciprocate bodily in a plane parallel with the plane of its cutting end, said reciprocating cutter being bodily adjusted on the carriage diagonally to the plane of the face of its cutting end and means for actuating the carrier; substantially as described.

7. In a trimming mechanism for sewing-machines, the combination with a relatively fixed cutter adjustable bodily toward and from the line of cut, of a reciprocating-cutter carrier, a carriage laterally adjustable on said carrier toward and from the line of cut, a cutter on the carrier diagonally supported relatively to the plane of the face of its cutting end and diagonally to the plane of the work-support and arranged to reciprocate bodily in a plane parallel with the plane of its cutting end, and means for actuating the carrier; substantially as described.

8. In a trimming mechanism for sewing-machines, the combination of a movable and a relatively fixed cutter, a carrier for the movable cutter, a carriage adjustably mount-

ed on the carrier and having a groove therein to receive the movable cutter the rear wall of which groove lies in a plane substantially at right angles to the plane of the cutter's movements and means for actuating the movable cutter, substantially as described.

9. In a trimming mechanism for sewing machines, the combination of a vibrating and a coöperating relatively fixed cutter, a carrier for the vibrating cutter, a carriage adjustably mounted on the carrier and having a diagonal groove therein in which the cutter is located, said groove extending in a plane substantially at right angles to the plane in which the cutter vibrates and being adapted to receive the pressure of the said cutter on its side wall, substantially as described.

10. In a trimming mechanism for sewing machines, the combination of coöperating cutters, one diagonally supported relatively to the plane of the face of its cutting end and diagonally to the plane of the work-support said cutter being provided with a wing guard or guide extending in the plane of the face of the cutting end whereby the face of the cutting end and wing-guard may be simultaneously dressed in a single plane and means for reciprocating one cutter bodily in a plane parallel with the plane of said cutting end; substantially as described.

11. In a trimmer for sewing-machines, a relatively fixed cutter in combination with a reciprocatory cutter formed by a bar having two longitudinally-extending wings or flanges, forming respectively a guard or guide and a cutting edge, the face of the cutting end and the guard or guide extending in a single plane whereby the cutting edge and wing-guard may be simultaneously dressed in a single plane for coöperation with the relatively fixed cutter without changing their shape; substantially as described.

12. In a trimmer for sewing-machines, the combination of an operating and a relatively fixed cutter, a support having a groove therein to receive the fixed cutter, a clamp mounted on the support and engaging the edge of the cutter to force the latter into engagement with the opposite wall of the groove said clamp having a wing or shoulder engaging the face of the said knife, substantially as described.

13. In a sewing-machine the combination of trimming mechanism, including a movable and a coöperating relatively fixed cutter, an adjustable carriage for the fixed cutter forming a support for the material on which the cutters operate and between which and the presser-foot the fabric or material may be clamped, substantially as described.

14. In a sewing-machine, the combination of a plate, a trimming mechanism including a movable and a coöperating relatively fixed laterally-adjustable cutter, a carriage for the fixed cutter, a support for the carriage and plate, a block on the support extending over the path of the carriage to support and laterally locate the plate, substantially as described.

15. In a trimming mechanism for sewing machines, the combination with a relatively fixed cutter, located below the plane of the work, of a reciprocatory cutter located above the plane of the work and formed by a bar having longitudinally-arranged wings or flanges one extending forwardly and forming a cutting edge and the other extending downwardly and forming a wing guard or guide for coöperation with the other cutter the end face of said flanges extending in a single plane parallel with the plane of reciprocation of the cutter; substantially as described.
